UNITED STATES PATENT OFFICE.

HENRY S. CARTER, OF CHICAGO, ILLINOIS.

DESIGN FOR LOUNGE AND SOFA BACKS.

Specification forming part of Design No. 7,355, dated April 7, 1874; application filed March 14, 1874.
 [Term of Patent 3½ years.]

To all whom it may concern:

Be it known that I, HENRY S. CARTER, of Chicago, in the county of Cook and State of Illinois, have invented a new and useful Improvement in Designs for Lounge and Sofa Backs, of which the following is a specification:

The object of the present invention is to produce a more elegant design for the backs of lounges and sofas. The nature of invention will be understood from the following:

The accompanying photographic illustration represents a lounge or sofa, the back of which represents my improvement in design.

A A B represent those ornaments nearest to the head of the lounge, and consist of a

scroll-carving, B, and upwardly-projecting turreted ornaments A A, which give a bold appearance to the configuration. That portion of the back nearest the foot of the lounge has a carved scroll, C, similar to B, and sets on the frame, which terminates in an ornamental arm, D.

I claim and desire to secure by Letters Patent—

A design for lounge and sofa backs, consisting of the configuration A B C D, as shown and described.

HENRY S. CARTER.
